JOSEPH H. ADDLER, OF BROOKLYN, NEW YORK, ASSIGNOR TO PULLCLEAN MANUFACTURING CORPORATION, OF BRIDGEPORT, CONNECTICUT, A CORPORATION OF DELAWARE

TOWEL CABINET

Application filed May 2, 1930. Serial No. 449,138.

This invention relates to towel cabinets of the type adapted to contain a so-called "continuous" towel, that is, a long length of towel, usually in roll form, which is adapted to be drawn outwardly through an opening in the cabinet in suitable predetermined lengths for drying purposes. This type of cabinet is usually provided with a roller mounted therein in position to be engaged and rotated by the towel as the latter is withdrawn from the cabinet, the said roller being effective, by the alternate stopping and releasing of the same, to control the feed of the engaged towel from the cabinet.

The object of the present invention is to provide an improved means for effecting the stopping and releasing of the said feed controlling roller. This means, in part, comprises a stop member, and a slidably mounted bolt carried by the roller in a manner to be partially projected from its support during rotation of the roller into position for engagement with said stop member, to thereby stop rotation of the roller and the consequent feeding or withdrawal of the towel, and the said stop member being operative to thereafter shift the bolt to stop releasing position for permitting further rotation of the roller and the consequent further feeding or withdrawal of the towel.

In the accompanying drawings illustrating my invention,

Fig. 1 is an end elevation of a cabinet equipped with my invention, with the outer casing in section and with the parts in roller stopping position.

Fig. 2 is a front view of that part of the cabinet containing the roller stopping and releasing mechanism, with the front wall of the casing partly broken away.

Fig. 3 is an enlarged sectional detail of the roller stopping and releasing mechanism showing the roller bolt in its retracted or inoperative position as effected by the stop device, which latter in effecting such operation serves also as a stop releasing device.

Fig. 4 is a similar view, but with the housing block carrying the stop device in elevation, showing the stop device in its normal position released from the roller bolt and roller

whereby the latter is free for further rotation as shown.

Fig. 5 is another similar view, but with both the stop and bolt carrying parts in elevation, showing the roller further advanced in its rotation and with the bolt projected into stop engaging position.

Fig. 6 is a front edge view of the bolt carrying disk.

Fig. 7 is a vertical section through the center of the same.

Fig. 8 is an enlarged sectional elevation on the line 8—8 of Fig. 1, looking in the direction indicated by the arrows.

Fig. 9 is a detail in top plan of the roller stopping and releasing mechanism, showing the action of a cam surface on the stop device housing block against the projecting end of the roller bolt, during the closing of the hinged cover of the cabinet casing on which said block is fastened.

The cabinet, which may be of any desired construction or design, is here shown as comprising an outer casing formed in two sections 2 and 3, the front section 3 being hinged at one of its vertical edges to the rear section 2, as at 4, whereby the casing may be opened to permit of ready access to the interior thereof.

Located within the casing adjacent its opposite ends are a pair of frame or bracket plates for the support of certain parts of the towel controlling mechanism to be presently described. Only one of these bracket plates, indicated at 5, is here shown, the same being secured in position by suitable fastening means, such as the bolts 6. The opposite bracket plate (not shown) is of like construction and similarly fastened in position.

Carried by these bracket plates is a shelf 7 upon which is supported the roll of clean towelling, indicated at 8. When so supported, the leading end of the towel is led from the front side of the roller up and over a guide 9, from thence downwardly and partially around a feed roller 10, suitably journaled in the end brackets, and from thence forwardly through an opening 10 in the front wall of the casing to and over a guide roller 11, which latter is journaled in extensions of the bracket plates 5.

et plates projected through the opening in the casing to support the roller 11 at the front side thereof as shown. From this guide roller the towel depends in loop form, as at 7, in convenient position for use; the towel at the rear side of the loop passing backwardly through the opening in the casing to a usual form of take-up or rewinding device comprising a pair of rollers 12 and 13, between which the towel is passed, the roller 12 being operative to pull the engaged towel into the cabinet and rewind it upon the roller 13. The roller 12 is operated in this way from the feed roller 9 when the latter is rotated by the frictional engagement therewith of the towel upon the withdrawal of the latter from the cabinet, the connection between the rollers being the usual chain and sprocket connection employed in these cabinets, such as the sprockets 15 and 16 rigidly attached to the respective rollers and engaged by the connecting chain 17.

As hereinbefore referred to, it is an object of the present invention to provide an improved means for controlling the feed or delivery of the clean towel whereby its withdrawal from the cabinet will be in predetermined lengths. This I accomplish by the provision of means for automatically stopping the roller 9 once upon each rotation thereof and thereby stopping the outward feeding or withdrawal of the towel; it being understood that the friction between the towel and the roller is such as to prevent movement of the towel independently of the roller under ordinary pulling strains such as exerted in the normal use of the cabinet.

The improved means for stopping rotation of the roller 9 as referred to comprises a bolt 20 slidably mounted in a transverse bore 21 formed in a housing block or disk 22 fixedly mounted on the squared end 23 of the spindle 24 which carries the feed roller 9; this bolt 20 being freely slidable in the bore 21 for movement transversely of the roller and being limited in its sliding movement by the engagement of the spindle end 23 with the end walls of an elongated groove 25 in the upper wall of the bolt, as best shown in Figs. 3 and 4. As a convenient means for placing the bolt in its bore 21 during the assembling of the parts, the disk 22 containing the bore is provided with an end cap 26 at one side of said bore which is removably held in position by suitable fastening means, such as screws 27.

When a length of towel is drawn out from the cabinet, thereby causing rotation of the engaged roller 9, the bolt 20 will slide outwardly from the roller connected disk 22 under the action of gravity as it moves downwardly from a horizontal position, so as to project its outer end beyond the disk, as shown in Fig. 5. During continued rotation of the roller, the said projecting end of the

bolt is brought into contact with the under face of a stop device 30, as shown in Figs. 1 and 8, and so stops rotation of the roller and thereby further withdrawal of the engaged towel. Subsequently, to obtain another length of towel, the bolt is released by the stop to permit another rotation of the roller. For effecting such release of the bolt, the stop device 30, in the present form of my invention, is in the form of a push button slidably mounted for horizontal movement in a housing block 31 on the inner wall of the casing, with its head 32 at the outer side of the casing for convenient engagement by the user, and with its inner or end face adapted for pressing engagement against an end face 33 of the bolt 20, which end face 33 is brought to a position opposite the end of the stop device upon the engagement with the latter of the projecting end of the bolt as shown in Fig. 1. By pressing inwardly upon the stop device at this time, it acts to move the bolt 20 backwardly into its bore in the disk 22, as shown in Fig. 3, following which the stop device, upon being released by the user, will be automatically returned by a spring 35 to its normal position, as shown in Figs. 1, 4 and 5, and thereby released from stopping engagement with the roller and its bolt 20. Thereafter the roller is free to make another rotation as shown in Figs. 4 and 5.

When the stop device is pushed inwardly to move the bolt to stop releasing position, as shown in Fig. 3, its inner end engages the roller disk 22 within a transverse notch 37 therein which intersects the open end of the bore 21, as best shown in Fig. 6. With the disk so engaged, further rotation of the roller and the consequent freedom of withdrawal of another length of towel is prevented until the user releases the push button and permits its return to normal position under the action of the spring 35. This control of the feed roller is important in that it prevents continued rotation of the roller when the bolt has been moved to its releasing position by the push button, until the latter is released by the user.

As hereinbefore stated, the housing block 31 which carries the combination stop and release device 30 is fastened on the front hinged section or cover 3 of the outer casing, such fastening being effected by suitable fastening means such as the bolts 39. It has been found in practice that if the bolt 20 is in a horizontally projected position, as in Figs. 1 and 9, upon the closing of the cover 3, the block 31, as heretofore made, will strike the end of said bolt and prevent closing of the cover without jamming or damage to some of the parts. Therefore, as a further feature of my present invention, I have provided said housing block with an extension 40 having an inclined or cam surface 41 positioned to engage the projecting end of the bolt 20 upon the closing of

the cover, as shown in Fig. 9, and force it backward into its bore 9 without jamming or injury to the parts.

What I claim is:

- 5 1. In a towel cabinet, the combination of a towel feed-controlling roller, a stop device, and a slidably mounted bolt carried by said roller adapted to be projected from its support during rotation of the roller into position for engagement with said stop at one side thereof, the said stop device and the bolt having end faces positioned opposite each other when the bolt is in engagement with the stop device and the latter being slidably mounted for movement in a direction to shift the bolt to stop releasing position.
- 10 2. In a towel cabinet, the combination of a towel feed-controlling roller, a stop device, and a slidably mounted bolt carried by said roller adapted to be projected from its support during rotation of the roller into position for engagement with said stop at the under side thereof, the said stop device and the bolt having end faces positioned opposite each other and above their stop engaging faces when the bolt is in engagement with the stop device and the latter being slidably mounted for movement in a direction to shift the bolt to stop releasing position.
- 15 3. In a towel cabinet, the combination with the outer casing thereof, of a towel feed-controlling roller, a stop device, and a slidably mounted bolt carried by said roller adapted to be projected from its support during rotation of the roller into position for engagement with said stop at one side thereof, the said stop device and the latter being slidably mounted within the casing for movement in a direction to shift the bolt to stop releasing position and having an operating part thereof at the outer side of the casing.
- 20 4. In a towel cabinet, the combination of a towel feed-controlling roller, a stationary support, a stop device slidably mounted in said support, and a slidably mounted bolt carried by the roller adapted to be projected from its support during rotation of the roller into position for engagement with said stop at the under side thereof, the said stop device and the bolt having end faces positioned opposite each other when the bolt is in engagement with the stop device and the latter being movable in a direction to shift the bolt to stop releasing position.
- 25 5. In a towel cabinet, the combination of a towel feed-controlling roller having a connected disk formed with a radial bore open at one end and a transverse notch intersecting said bore, a stationary support, a stop device slidably mounted in said support, a bolt slidably mounted in said bore of the roller disk and adapted to be projected there-

from during rotation of the roller into position for engagement with said stop device, the said stop device and the bolt having end faces positioned opposite each other when the bolt is in engagement with the stop device and the latter being movable in a direction to shift the bolt to stop releasing position and at the same time enter the transverse notch of the roller disk to effect latching engagement with the latter, and means for automatically returning the stop device to its normal position of disengagement from the roller disk and its supported bolt.

6. In a towel cabinet, the combination with the outer casing having a hinged cover, of a towel feed-controlling roller, a stop device mounted on said cover, a slidably mounted bolt carried by the roller adapted to be projected from its support during rotation of the roller into position for engagement with said stop at one side thereof, and means on said cover operative upon the closing of the latter to engage the projecting end of the bolt and return it to its retracted position.

7. In a towel cabinet, the combination with the outer casing having a hinged cover, of a towel feed-controlling roller, a stop device mounted on said cover, a slidably mounted bolt carried by the roller adapted to be projected from its support during rotation of the roller into position for engagement with said stop at one side thereof, and a cam device on said cover operative upon the closing of the latter to engage the projecting end of the bolt and return it to its retracted position.

8. In a towel cabinet, the combination with the outer casing having a hinged cover, of a towel feed-controlling roller, a block mounted on said cover carrying a stop device, and a slidably mounted bolt carried by the roller adapted to be projected from its support during rotation of the roller into position for engagement with said stop at one side thereof, the said block on the cover having a cam surface positioned and operative upon the closing of the cover to engage the projecting end of the bolt and return it to its retracted position.

In testimony whereof I affix my signature.

JOSEPH H. ADDLER.
